FLEXIBLE PACKAGE FOR LIQUID OR THE LIKE

Edoardo Cigognetti, Via della Repubblica 19,
Senago, Milan, Italy

Filed Apr. 17, 1961, Ser. No. 64,782

Claims priority, application Italy Oct. 29, 1960

Term of patent 7 years

(Cl. D58—2)

FIG. 1 is a top plan view of a flexible package for liquid or the like, showing my new design;

FIG. 2 is a front elevational view thereof;

FIG. 3 is a left-side elevational view thereof; and

FIG. 4 is a right-side perspective view thereof.

I claim:

The ornamental design for a flexible package for liquid or the like, as shown.
